United States Patent Office.

ALEXANDER CARMICHEL, OF WESTERLY, RHODE ISLAND, ASSIGNOR TO HIMSELF, JONATHAN P. STILLMAN, AMES STILLMAN, ALBERT STILLMAN, AND THOMAS V. STILLMAN, OF SAME PLACE.

Letters Patent No. 102,772, dated May 10, 1870.

IMPROVEMENT IN SPOOLS OR BOBBINS.

The Schedule referred to in these Letters Patent and making part of the same.

To all whom it may concern:

Be it known that I, ALEXANDER CARMICHEL, of Westerly, in the county of Washington and State of Rhode Island, have invented certain new and useful Improvements in the Construction of Spools and Bobbins; and I do hereby declare that the following is a full and exact description thereof.

My invention is intended to give increased strength and durability to the articles with the same weight, or about the same, as when entirely of wood, and with but a slight increase in the cost. It is of especial advantage in avoiding the roughness experienced with the ordinary wood spools and bobbins, when they are partially worn out, and which frequently results in catching fine-yarns or rovings and causing them to break.

I cover the peripheries and inner faces of the rims or flanges with a casing of thin metal, or analogous material, which wears smoothly.

I will proceed to describe what I consider the best means of carrying out my invention.

The accompanying drawings form a part of this specification.

Figure 1 is a side view, partly in section, of the entire spool.

Figure 2 is a section of the wood portion only of a head. This is an ordinary form and construction adapted to be covered, but to which the cover has not yet been applied.

Figure 3 is a view of the metal with a portion broken away. It shows the material of the cover when first cut out, and while in a plane condition.

Figure 4 shows the same after one operation of the dies, not represented.

Figure 5 shows the same after the wood portion and the covering material has been applied together, but before being finally compressed together so as to fold the covering upon the wood.

Figure 6 shows the same after the covering is partly folded down upon the wood.

By turning now again to fig. 1, it will appear that the covering is there closely folded down upon the wood.

Similar letters of reference indicate like parts in all the figures.

A is the body or barrel, and

B¹ B² are two thicknesses of wood glued with their grain crossing each other, which together form the head. They are secured to the barrel preferably by both screw-threads and glue. The outer edge of the flange or head is rounded. The two heads may be alike, or one may be thicker, or in any way varied from the other, as may be desired. What are termed bobbins are usually analogous in structure, but with only one head. The heads may be of various kinds of wood, but I esteem it important that they are made primarily of wood, in two thicknesses glued to-

gether, the grain of the wood in one thickness crossing the grain of the wood in the other thickness, as above described.

So far as is yet described the structure is identical with those long known, and in common use.

To encase the inner faces and periphery of a head, I take a sheet of tinned iron, cut in a circular form, and having a hole in the center a little less in diameter than the exterior of the barrel or body A of the spool. I strike this flat disk of iron between convex and concave dies, so as to turn up the periphery. I fit into this the wood head of the bobbin, and then, by means of one or more other dies, bend the turned-up edge firmly over, and compress it into the wood of the head, in the position represented by d in fig. 1.

This cased head is now ready to be firmly united to the barrel A by the ordinary, or any suitable means, and fulfills admirably the functions, not only of strengthening the union of the two thicknesses B¹ B² together, aiding to defend the entire head against splitting or other breakage in case of falling upon the floor, or other violence, but also of insuring a smooth inner face to rub against the yarn in the act of being drawn off.

In the use of spools or bobbins for some purposes, the yarn is drawn directly over the end. In such case it is highly important, not only that the inner face of the heads, but also the entire periphery of the head shall be smoothly cased. My casings, by extending not only over the entire inner faces, but also over the entire periphery, fulfil this end very perfectly in addition to the others before enumerated.

It will be observed that my casing, by extending inward to and a little within the barrel, covers the whole inner surface of the head, and avoids the risk of thread or rovings being caught on the inner edge, which, in use, is liable to get rough and to project. Also, that by the embracing of both thicknesses of my crossed wood at the periphery of the head, they are aided in holding firmly and inseparably together. And also, that being struck up and compressed on the wood, as explained, the damage due to the heat of casting on a metal casing is avoided.

I claim—

A spool or bobbin, having a head of wood in two thicknesses with the grain crossed, and a hard casing of metal extending over the entire inner surface and over the periphery, so as to coat and strengthen the surfaces and bind the wood together, when the casing is formed and applied without injury to the wood, and in the manner and for the purposes herein set forth.

In testimony whereof I have hereunto set my name in presence of two subscribing witnesses.

ALEXANDER CARMICHEL.
